UNITED STATES PATENT OFFICE.

LONGLEY LEWIS SAGENDORPH, OF PHILADELPHIA, PENNSYLVANIA,
ASSIGNOR OF ONE-HALF TO CHARLES N. HARDER, OF PHILMONT,
NEW YORK.

DESIGN FOR A ROOFING-PLATE.

SPECIFICATION forming part of Design No. 20,531, dated February 24, 1891.

Application filed January 21, 1891. Serial No. 378,598. Term of patent 14 years.

To all whom it may concern:

Be it known that I, LONGLEY LEWIS SAGENDORPH, a citizen of the United States, residing at Philadelphia, in the county of Philadelphia, State of Pennsylvania, have invented and produced a new and original Design for Metallic Roofing-Plates, of which the following is a specification, reference being had to the accompanying drawings, forming a part thereof.

My design consists of a metallic plate having raised figures cubical in outline, said figures being arranged alternately in a longitudinal line, as shown.

15 In the drawings, Figure 1 is a plan view of a metallic sheet embodying my design. Fig. 2 is a longitudinal section taken on the line xx of Fig. 1, and Fig. 3 is a cross-section taken on the line yy of said Fig. 1.

20 As shown in the drawings, the raised cubical figures A are arranged alternately in a longitudinal line and the end of each figure gradually slants from the highest point a at one corner of the figure to the lowest point b

at the opposite corner, as more clearly shown 25 in Fig. 2. It will also be seen that a straight line drawn from any one of the highest points a will pass through the intersecting points c and will represent the length of two figures before touching the lowest point b . (See Fig. 30 2.) The raised cubical figures may be of any desired size.

A sheet of metal embodying my design is ornamental in appearance and may be used in any capacity—*i. e.*, ceiling-plates or for 35 siding.

What I claim is—

The design for metallic roofing-plates herein shown and described, the same consisting of a series of raised cubical figures A, arranged alternately in a longitudinal line, said figures gradually tapering from the highest point a to the lowest point b , as set forth.

LONGLEY LEWIS SAGENDORPH.
